SASH BALANCE

August Viehweger, Grand Rapids, Mich., assignor
to Grand Rapids Hardware Company, Grand
Rapids, Mich., a corporation of Michigan

Application August 3, 1944, Serial No. 547,822

11 Claims.

(Cl. 16—197)

This invention relates to improvements in sash balances.

The main objects of this invention are:

First, to provide a spring sash balance which is very compact when completely collapsed and at the same time is adapted for use on windows of different vertical dimensions.

Second, to provide a sash balance which may be easily installed when the spring is adjusted to the desired tension or the particular load incident to the particular installation.

Third, to provide a sash balance having these advantages which is economical in its parts and in the assembly thereof.

Fourth, to provide a sash balance which operates freely even though great care is not exercised in the installation thereof, thereby permitting installation by relatively unskilled workmen.

Objects relating to details and economies of the invention will appear from the description to follow. The invention is defined and pointed out in the claims.

Preferred embodiments of the invention are illustrated in the accompanying drawing, in which:

Fig. 1 is a fragmentary view partially in vertical section of a window and window frame or casing with a balance embodying my invention in operative relation thereto, the balance being shown in fully extended position as results when the window is in closed position.

Fig. 2 is a fragmentary view corresponding to that of Fig. 1 with the window in fully open position.

Fig. 3 is an enlarged fragmentary view partially in vertical section on a line corresponding to line 3—3 of Fig. 1.

Fig. 4 is an enlarged horizontal section on line 4—4 of Fig. 1.

Fig. 5 is an enlarged fragmentary view partially in vertical section on line 5—5 of Fig. 1.

Fig. 6 is a fragmentary view of a modified form or embodiment of my invention, the modification being in the mounting bracket.

Fig. 7 is an enlarged fragmentary view partially in longitudinal section of a modified form or embodiment of my invention.

In the accompanying drawing, 1 represents a window frame or casing and 2 a window sash having a groove 3 in the edge thereof, the groove being of such dimensions as to receive the sash balance.

The embodiment of my invention illustrated comprises a pair of telescopingly associated outer and inner tubular elements 4 and 5 respectively.

These elements have spiral grooves 6 and 7, the grooves illustrated being in the form of slots and resulting from the spiral twisting of a strip of metal into tubular form with the winds thereof in properly spaced relation to form the grooves.

At the outer end of the outer element 4 the groove 6 is provided with a lateral recess 8, the ends 9 of which constitute a stop. The inner end of the groove 7 of the element 5 is provided with a corresponding recess 10 and stop 11.

The sleeve-like torsion member 12 is provided with an attaching arm 13. This constitutes an attaching bracket, the sleeve slidably embracing the outer element 4. This torsion member is provided with an inwardly projecting lug-like member 14 which engages the groove 6 in the outer tubular element 4, this groove-engaging member 14 being within the recess 8 and engaging the stop 9 when the balance is fully extended as shown in Fig. 1.

At its inner end, the outer element 4 is provided with a lug-like groove-engaging member 15 which engages the groove in the inner element 5 and when the balance is fully extended, lies within the recess 10 and coacts with the stop 11 to limit the extension of the tubular elements.

The coiled balancing spring 16 is arranged within the inner tubular element, the inner end of the spring being engaged with the clutch pin 17 extending inwardly from the support 18 which is secured within the inner end of the inner element 5 by striking a portion 19 thereof into a recess 20 formed in the member 18. The lower end of the spring is engaged with the inner end 21 of the tension rod 22, this inner end 21 constituting a clutch pin. The tension rod extends through the bushing 23 in the outer end of the inner element, the bushing being held in place by the indentation 24 engaging the slot 25 in the bushing, see Fig. 5.

The tension rod is pivotally secured at 26 to the bracket 27 which, in the embodiment illustrated, is attached to the bottom or lower end of the sash, as shown in Fig. 1. It will be understood that the parts might be reversed. The tension rod constitutes a journal for rotatably supporting the outer end of the inner element 5.

In the embodiment shown in Fig. 6, the tension rod 39 is provided with a bracket extension 28 formed integrally therewith.

The embodiment shown in Figs. 1 to 5, however, has advantages in that the parts are permitted to adjust themselves to varying conditions without binding and less care is required in installing both these embodiments. However, the desired

tension is applied to the spring before the bracket is secured.

In the embodiment shown in Fig. 7, the inner tubular element has a sleeve 29 secured within the inner end thereof—in the structure illustrated by means of a lug 38 struck into the slot 31. The lower end of this sleeve has ratchet teeth 32 with which the ratchet teeth 33 of the tension member 34 coact, this tension member being slidable within the tubular element and having a rod-like extension 35 on its upper end slotted to receive an adjusting tool 36. The inner end of this rod constitutes a clutch pin 37 for the inner end of the spring. With this arrangement, the tension of the spring can be adjusted after the bracket 27 has been attached.

With this arrangement of parts, the balance may be collapsed for shipment and storage, thus greatly reducing the packaging and shipping space, may be quickly and easily installed in varying sizes of windows and adjusted or tensioned to provide the required counterbalancing tension or torsion on the spring.

In operation, both inner and outer members are subject to the torsional stress of the spring and when the window is closed the members or elements are extended. When the window is open the elements are telescoped, as shown in Fig. 2.

I have illustrated and described certain practical embodiments of my invention which it is believed will enable those skilled in the art to embody and adapt the same as may be desired. I have not attempted, however, to illustrate other embodiments or adaptations which I contemplate.

Having thus described my invention, what I claim as new and desire to secure by Letters Patent, is:

1. In a sash balance, the combination of a pair of telescopingly associated inner and outer tubular elements, each having a spiral groove extending substantially from end to end thereof, the outer end of the groove of the outer tubular element and the inner end of the groove of the inner element both terminating in lateral recesses provided with stops at their outer ends, said outer element being provided with an inwardly projecting groove-engaging member at its inner end coacting with the groove of said inner element and with said recess at the inner end thereof, a torsion member constituting an attaching bracket provided with a sleeve slidably receiving said outer element and provided with a groove-engaging member coacting with the groove of said outer element, a bushing secured within the outer end of the inner element, a second attaching bracket, a tension rod pivoted to said second attaching bracket and journaled within said bushing and projecting inwardly therefrom to provide a spring clutch pin, a spring clutch pin secured within the inner end of said inner element, and a coiled spring arranged within said inner element with its ends in clutching engagement with said clutch pins, said groove engaging members being urged into said recesses by said spring and constituting detents coacting therewith.

2. In a sash balance, the combination of a pair of telescopingly associated inner and outer tubular elements, each having a spiral groove extending substantially from end to end thereof, the outer end of the groove of the outer tubular element and the inner end of the groove of the inner element both terminating in lateral recesses provided with stops at their outer ends, said outer element being provided with an inwardly projecting groove-engaging member at its inner end co-

acting with the groove of said inner element and with said recess at the inner end thereof, a torsion member constituting an attaching bracket provided with a sleeve slidably receiving said outer element and provided with a groove-engaging member coacting with the groove of said outer element, a bushing secured within the outer end of the inner element, a tension rod provided with an attaching bracket and journaled within said bushing and projecting inwardly therefrom to provide a spring clutch pin, a spring clutch pin secured within the inner end of said inner element, and a coiled spring arranged within said inner element with its ends in clutching engagement with said clutch pins, said groove-engaging members being urged into said recesses by said spring and constituting detents coacting therewith.

3. In a sash balance, the combination of a pair of telescopingly associated inner and outer tubular elements, each having a spiral groove extending substantially from end to end thereof, said outer element being provided with an inwardly projecting groove-engaging member at its inner end coacting with the groove of said inner element, a torsion member constituting an attaching bracket provided with a sleeve slidably receiving said outer element and provided with a groove-engaging member coacting with the groove of said outer element, a bushing secured within the outer end of the inner element, a second attaching bracket, a tension rod pivoted to said second attaching bracket and journaled within said bushing and projecting inwardly therefrom to provide a spring clutch pin, a spring clutch pin secured within the inner end of said inner element, and a coiled spring arranged within said inner element with its ends in clutching engagement with said clutch pins.

4. In a sash balance, the combination of a pair of telescopingly associated inner and outer tubular elements, each having a spiral groove extending substantially from end to end thereof, said outer element being provided with an inwardly projecting groove-engaging member at its inner end coacting with the groove of said inner element, a torsion member constituting an attaching bracket provided with a sleeve slidably receiving said outer element and provided with a groove-engaging member coacting with the groove of said outer element, a bushing secured within the outer end of the inner element, a tension rod provided with an attaching bracket and journaled within said bushing and projecting inwardly therefrom to provide a spring clutch pin, a spring clutch pin secured within the inner end of said inner element, and a coiled spring arranged within said inner element with its ends in clutching engagement with said clutch pins.

5. In a sash balance, the combination of a pair of telescopingly associated inner and outer tubular elements, each having a spiral groove extending substantially from end to end thereof, the outer end of the groove of the outer tubular element and the inner end of the groove of the inner element both terminating in lateral recesses provided with stops at their outer ends, said outer element being provided with an inwardly projecting groove-engaging member at its inner end coacting with the groove of said inner element and with said recess at the inner end thereof, a torsion member provided with a sleeve slidably receiving said outer element and provided with a groove-engaging member coacting with the groove of said outer element, an attaching

bracket, a tension rod carried by said attaching bracket and constituting a journal for said inner element, and a coiled spring arranged within said inner element with one end connected to said tension rod and the other connected to the inner end of said inner element, said groove-engaging members being urged into said recesses by said spring and constituting detents coacting therewith.

6. In a sash balance, the combination of a pair of telescopingly associated inner and outer tubular elements, each having a spiral groove extending substantially from end to end thereof, said outer element being provided with an inwardly projecting groove-engaging member at its inner end coacting with the groove of said inner element, a torsion member provided with a sleeve slidably receiving said outer element and provided with a groove-engaging member coacting with the groove of said outer element, an attaching bracket, a tension rod carried by said attaching bracket and constituting a journal for said inner element, and a coiled spring arranged within said inner element with one end connected to said tension rod and the other connected to the inner end of said inner element.

7. In a sash balance, the combination of a pair of telescopingly associated inner and outer tubular elements, each having a spiral groove extending substantially from end to end thereof, the outer end of the groove of the outer tubular element and the inner end of the groove of the inner element both terminating in lateral recesses, said outer element being provided with an inwardly projecting groove-engaging member at its inner end coacting with the groove of said inner element and with said recess at the inner end thereof, a torsion member constituting an attaching bracket and with which said outer element is slidably associated and provided with a groove-engaging member coacting with the groove of said outer element, an attaching bracket for rotatably supporting said inner element, a coiled spring arranged within said inner element for applying torsional stress thereto, said groove engaging members being urged into said recesses by said spring and constituting detents coacting therewith, and means for adjusting the tension of said spring.

8. In a sash balance, the combination of a pair of telescopingly associated inner and outer tubular elements, each having a spiral groove extending substantially from end to end thereof, said outer element being provided with an inwardly projecting groove-engaging member at its inner end coacting with the groove of said inner element, a torsion member constituting an attaching bracket and with which said outer element is

slidably associated and provided with a groove-engaging member coacting with the groove of said outer element, an attaching bracket for rotatably supporting said inner element, and a coiled spring arranged within said inner element for applying torsional stress thereto.

9. In a sash balance, the combination of a pair of telescopingly associated inner and outer tubular elements, each having a spiral groove extending substantially from end to end thereof, the outer end of the groove of the outer tubular element and the inner end of the groove of the inner element being provided with stops, said outer element being provided with an inwardly projecting groove-engaging member at its inner end coacting with the groove of said inner element, a relatively fixed torsion member with which said outer element is slidably associated and provided with a groove-engaging-member coacting with the groove of said outer element, means for rotatably supporting said inner element, and a coiled spring arranged within said inner element for applying torsional stress thereto, said groove-engaging members being urged into said recesses by said spring and constituting detents coacting therewith.

10. In a sash balance, the combination of a pair of telescopingly associated inner and outer tubular elements, each having a spiral groove extending substantially from end to end thereof, said outer element being provided with an inwardly projecting groove-engaging member at its inner end coacting with the groove of said inner element, a relatively fixed torsion member with which said outer element is slidably associated and provided with a groove-engaging member coacting with the groove of said outer element, means for rotatably supporting said inner element, and a coiled spring arranged within said inner element for applying torsional stress thereto.

11. In a sash balance, the combination of a pair of telescopingly associated inner and outer tubular elements, each having a spiral groove extending substantially from end to end thereof, said outer element being provided with an inwardly projecting groove-engaging member at its inner end coacting with the groove of said inner element, a relatively fixed torsion member with which said outer element is slidably associated and provided with a groove-engaging member coacting with the groove of said outer element, means for rotatably supporting said inner element, a coiled spring arranged within said inner element for applying torsional stress thereto, and means for adjusting the tension of said spring.

AUGUST VIEHWEGER.
